PATENTED NOV. 5, 1907.

P. T. DODGE.
LINOTYPE MACHINE.
APPLICATION FILED MAR. 27, 1906.

UNITED STATES PATENT OFFICE.

PHILIP T. DODGE, OF BROOKLYN, NEW YORK, ASSIGNOR TO MERGENTHALER LINOTYPE COMPANY, A CORPORATION OF NEW YORK.

LINOTYPE-MACHINE.

No. 870,019.

Specification of Letters Patent.

Patented Nov. 5, 1907.

Application filed March 27, 1906. Serial No. 308,359.

To all whom it may concern:

Be it known that I, PHILIP TELL DODGE, of the borough of Brooklyn, county of Kings, and State of New York, have invented a new and useful Improvement 5 in Linotype-Machines, of which the following is a specification.

My invention has reference to linotype machines of the general character represented in Letters Patent of the United States #436,532, and kindred machines, 10 wherein circulating matrices, representing the various characters, are stored in channeled magazines from which they are delivered by escapement mechanisms and finger keys, one at a time, to be composed in lines for presentation to a casting mechanism. These machines are commonly constructed in such manner that the magazine may be removed and replaced by another containing matrices for type faces of a different size or style. Heretofore it has been the general practice to provide each magazine with an escapement 15 mechanism incorporated permanently therein and forming a part thereof. The escapement mechanism is complicated and expensive, and in order to avoid the expense of an escapement mechanism for each magazine, it has been proposed to make the same a 20 unitary structure and secure it permanently to the main frame so that the magazine may be independently removed and various magazines used with the one escapement mechanism. Owing to the fact that the escapement devices must be constructed and ad- 25 justed in relation to each other and to the magazine with extreme precision, the last-named construction demands costly tools and is very expensive. Beyond this, it is open to the objection that the slightest springing or bending of the parts will prevent the 30 magazine and escapements from coming together in their proper relations.

The object of my invention is to attain the advantages of both the older constructions without the disadvantages of either. To this end, I construct the magazine and the escapement mechanism each as a complete unitary structure, and connect them by devices which will admit of their being readily separated so that the magazine seated on and supported by the main frame will serve in turn to support the escapement 45 mechanism connected firmly thereto. This construction insures the proper relationship of the magazine and the escapements, and permits the use of the one escapement mechanism with a number of magazines.

The escapement mechanism including the escapements proper, their supporting bar, and their actuating springs may be removed from the machine with the magazine, and thereafter separated and applied to a second magazine, but I prefer to disconnect the escapement from the magazine before the latter is removed. When disconnected the escapement mech-

anism may be left loose on the main frame or other support in position to be connected to the next magazine which may be applied to the machine.

The form of the escapement devices and the details of the connections between the escapements and the magazine may be widely varied within the limits of mechanical skill and without passing beyond the scope of my invention.

Referring to the drawings,—Figure 1 is a vertical central section from front to rear through a magazine, 65 escapement mechanism and the attendant parts, constructed in accordance with my invention, the parts being in operative position. Fig. 2 is a similar view with the magazine detached from the escapement and lifted preparatory to its removal. Fig. 3 is a similar 70 section showing the parts in a modified or alternative form.

Referring to the drawings, A represents the rigid main frame, which may be of any suitable construction.

B is the inclined longitudinally channeled magazine adapted to receive and carry the matrices C, as usual.

D is a vertically movable base frame, underlying and supporting the magazine secured in the main frame and forming in effect a part thereof.

E is the vertically channeled front plate or raceway into which the matrices are delivered from the respective channels of the magazine, from which they pass to the usual assembling mechanism.

F represents the escapement mechanism consisting of 85 a rigid bar or frame f, of any suitable construction, containing the series of escapement levers f', each lever being mounted on a central pivot and provided on its ends with two upwardly extending pawls which are projected alternately upward through the bottom of the magazine by the oscillation of the lever. There is one of these escapement levers for each channel of the magazine, and in their general form and arrangement they operate to release the matrices one at a time in the same manner as in the commercial linotype machine of the 95 present day. Each escapement lever is acted upon by a spring f² attached to a flange on the escapement bar and tending to draw the lower escapement downward from the magazine. Each escapement is also acted upon by a vertically reciprocating bar or reed G urged 100 constantly downward by a spring H sufficiently strong to overcome the spring f². The finger key mechanism is connected with the bars G in the same manner as in the ordinary linotype machines, or in any other suitable manner, to lift the bars and permit the escapements to 105 reverse their positions and deliver the matrices. The reeds G will be guided as usual by movable supports, this being an ordinary feature in all linotype machines and foreign to the present invention.

If the escapement mechanism is removed while the 110

magazine is in the machine and filled with matrices they should be locked in the magazine to prevent their accidental escape. Various devices are known for this purpose—such as the transverse removable rods shown 5 at N in United States Patent No. 548,432, or the rock shafts L as shown in the Patent 776,779.

It will be observed that the under plate of my magazine, which gives support to the matrices, is continuous and extended to the lower extremity of the magazine 10 so that the matrices may be confined and supported in the magazine when it is removed from the machine, holes or slots being formed in said under plate to permit the upper ends of the escapement pawls to rise therethrough.

15 The escapement bar and its pawls and levers constitute in themselves a complete or unitary structure wholly independent of the magazine and of the main frame. The escapement bar is applied to the under side of the magazine and is secured firmly but removably thereto in the exact position required, by locking devices which may be of any suitable form, provided they are adapted to effect its instantaneous connection and release.

20 In Fig. 1, the connecting devices consist of transverse keys or bars I and I', each seated at one edge in a groove in the escapement bar, and at the opposite edge in a bar J, secured rigidly and permanently to the under side of the magazine and forming part thereof. The escapement is not seated upon, connected to or sustained by 25 the main frame. On the contrary, it is secured by the bars J directly and rigidly to the magazine so that it receives support therefrom. By thus attaching the escapement directly and firmly to the magazine, I am enabled to prevent it from warping, twisting or changing 30 its relation to the magazine, and consequently each and every pawl is compelled to rise and fall the exact distance required with reference to the upper surface of the magazine plate and the matrices riding thereon.

35 When the escapement mechanism is to be disconnected, it is only necessary to withdraw the bars or keys I endwise thereby permitting the escapement bar to fall away from the magazine; or, if preferred, the escapement bar may be withdrawn endwise as hereinafter described.

40 When the magazine is to be removed, it is preferably lifted clear of the channel plate E by raising the frame D, as shown in Fig. 2, after which the magazine may be removed from the machine in a forward direction. This may be done before the escapements are disconnected 45 so that they may be detached after the magazine has been removed from the machine. In such case, the escapement mechanism will be secured to a second magazine before it is in turn applied to the machine. I prefer, however, to effect the disconnection of the escapement before the magazine is lifted and removed, 50 as indicated in Fig. 2. In such case, the escapement, when released, will fall slightly away from the magazine and from its operative position, and rest temporarily on the main frame or other support, so that it will 55 be in convenient position to be lifted into engagement with the second magazine when it is in operative position.

60 Instead of the sliding bars represented in Figs. 1 and 2, I may employ two rotary locking bars I², flattened on 65 one side and seated in opposite sides of the escapement

mechanism, the form and arrangement being such that after the magazine is in place, the escapement may be lifted into contact therewith and secured by turning the bars. A skilled mechanic will understand that these locking devices may be made in a great variety of forms, 70 the only requirement being that the escapement mechanism shall be firmly secured along its two longitudinal edges to the magazine.

It will be observed that in Figs. 1 and 2 the under side of the magazine, although of full length, is provided with two transverse slots b and b' to receive ribs on the upper side of the escapement frame, these ribs serving to guide the escapement pawls to their extreme upper ends, and also serving to fill the slots when the escapement is locked in its operative relation to the 80 magazine, the ribs forming in effect a part of the under plate of the magazine. These ribs are not, however, a necessary feature of the construction, and the under plate of the magazine may be made continuous, as shown in Fig. 3, with only small holes therethrough for 85 the passage of the upper ends of the pawls. When the magazine is grooved on the under side, the escapement bar may be inserted and removed endwise. In such case, the locking bars I and I' may be secured permanently in place to the magazine or to the escapement 90 mechanism or replaced by a tongue formed in either of these parts and extending into the other.

The removal of the escapement bar endwise from the magazine is of advantage in that it permits all the escapements to be instantly withdrawn from the machine—as is often necessary in order to repair, clean, or adjust them, or to remove any obstructions—without removing the magazine or otherwise disorganizing the machine.

95 While I prefer to employ escapement levers in the 100 form shown—the form in general use—it will, of course, be understood that they may be varied at will, a number of suitable forms being already known in the art.

Having described my invention, what I claim is:—

1. In a linotype machine, the combination of a main frame, a magazine mounted thereon and adapted as described to contain all the matrices in a set or font, and escapement mechanism complete in itself, and means connecting the magazine and escapement mechanism, said means adapted to permit the instantaneous and entire 110 disconnection of the escapement mechanism from the magazine.

2. As an improvement in linotype machines, a magazine complete in itself and adapted to carry an entire set or font of matrices, and an escapement mechanism complete in itself, said magazine and escapement mechanism being connected by means substantially as shown adapted to permit their instantaneous and entire disconnection.

3. A magazine having channelled top and bottom plates extended to the extreme lower end with openings in the under side to admit the operative ends of escapements, in combination with escapement mechanism comprising a bar and pivoted escapements therein, and locking connections between the two edges of the escapement bar and the magazine, said connections adapted to permit the instantaneous separation of the parts.

4. A magazine having rigid parallel bars on its under side in combination with the escapement mechanism removably secured between said bars.

5. In a linotype machine, the combination of an inclined channelled magazine removable at will, an escapement mechanism complete in itself, means for instantly effecting a rigid connection and disconnection of the magazine and escapement mechanism, and a main frame adapted to support the magazine and also adapted to sup-

port the escapement mechanism only after its disconnection from the magazine.

6. In a linotype machine, the combination of a main-frame, a magazine, mounted thereon and adapted to contain all the matrices in a set or font, an escapement mechanism complete in itself, and connections through which the escapement mechanism is sustained from the magazine, said connections adapted to permit the instantaneous and entire disconnection of the escapement mechanism from the magazine.

7. In combination, a longitudinally channeled magazine and a co-operating escapement mechanism comprising a series of escapements, a supporting bar therefor, and escapement actuating springs, said mechanism secured transversely to the magazine, substantially as described and removable therefrom lengthwise of the bar at will.

8. A longitudinally channeled magazine, in combination with a series of escapements acting through the side of the magazine, and a bar wholly sustaining the escapements, said bar secured to the magazine by longitudinal sliding connections adapted to permit the removal of the bar at will in an endwise direction with the escapements therein.

In testimony whereof I hereunto set my hand this twenty-fourth day of March, 1906, in the presence of two attesting witnesses.

PHILIP T. DODGE.
